UNITED STATES PATENT OFFICE.

ANDREW J. MAPES, OF PARIS, ILLINOIS.

HORSE-CANOPY.

SPECIFICATION forming part of Letters Patent No. 705,370, dated July 22, 1902.

Application filed March 14, 1902. Serial No. 98,167. (No model.)

To all whom it may concern:

Be it known that I, ANDREW J. MAPES, a citizen of the United States, residing at Paris, in the county of Edgar and State of Illinois, have invented new and useful Improvements in Canopy Horse Shades and Fans, of which the following is a specification.

My invention relates to an improvement in folding canopies for horses, and is adapted to be applied to the tongue or shafts of a wagon and may be folded up and extended by the driver without leaving the wagon.

The invention is more particularly described in the annexed specification and drawings, in which—

Figure 1 shows a top plan view of the canopy extended. Fig. 2 is a side view showing the canopy attached to the tongue T of a wagon for two horses. Fig. 3 shows an end view, and Fig. 4 shows a construction for attachment to the shafts of a wagon for one horse.

The frame comprises the standards R, which have means for attachment to the tongue T, said means consisting of clamps M. The upper ends of the standards R are connected to two blocks A, which are united by a longitudinal rod F. The blocks A carry extensions C, to which are pivoted arms B, to which the canopy is secured. The pivots are some distance from the inner ends of the arms, so as to permit the attachment of coil-springs D, which normally throw the arms out to expand and spread the canopy. The canopy is folded by means of cords E, attached to the outer ends of the arms B and leading over pulleys P P on the rod F to convenient fastening means O on the rear standard R. When the cords are released, the springs D will throw the arms B outward, thus spreading the canopy. The cords E are pulled in when it is desired to fold the canopy.

Fig. 4 shows the same form of canopy, the standards R being arched instead of straight, so as to be readily attached to the shafts S of a wagon. Any form of clamp M desired may be used, such clamp not being a part of my invention.

It will be observed that the canopy will serve to protect the animal from the weather and also will produce a current of air when the animal is moving, due to the up-and-down motion of the tongue or shafts.

Having ascertained and described my invention, what I claim, and desire to secure by Letters Patent of the United States, is—

1. The combination, in a canopy for horses, of the standards carrying the main frame-bar, said frame-bar having a block A at each extremity, provided with lateral extensions, with arms B pivoted intermediate their ends to said extensions, springs D attached at one end to one end of said arms and at the other end to the blocks A, cords E attached to the other ends of said arms, and means for guiding and fastening said cords, as set forth.

2. In a canopy-support, the frame carrying pivoted arms to which the canopy is attached, springs for throwing said arms normally outward, means for controlling the outward movement of said arms and holding the same in a closed position upon the frame, and means for supporting the frame upon a vehicle above the horse, whereby the action of the animal under the cover will give resiliency motion to the spring-supported canopy thereby creating a constant air movement beneath the canopy, as set forth.

ANDREW J. MAPES.
